ATTORNEY

UNITED STATES PATENT OFFICE

WILLIAM G. SHELTON, OF ST. LOUIS, MISSOURI

HAIR DRIER

Application filed December 17, 1928. Serial No. 326,584.

My invention relates to hair driers, such as are in use in beauty parlors, and consists in novel housing, operating structure and switch arrangement.

5 One of the objects of my invention is to provide a housing or casing for the operating parts which will be simple and of neat appearance, strong and easily cleaned.

Another object of my invention is to arrange 10 a motor, a fan, heating elements and a therapeutic lamp in such relation that the air currents created by the fan will pass over the motor, tending to cool the same, will receive the maximum amount of heat from the 15 heating element and from the lamp, and will be directed from the drier with a minimum amount of interference in their passage therethrough.

Another object of my invention is to arrange 20 the circuits and control switches therefor so that the device may be most easily and effectively operated.

In the accompanying drawings which illustrate 25 a selected embodiment of my invention—

Figure 1 is a longitudinal vertical section through my device.

Figure 2 is an elevation of the left hand end of the device as illustrated in Figure 1. 30 Figures 3 and 4 are vertical sections taken on the lines 3—3 and 4—4 of Figure 1.

Figure 5 is a wiring and switch diagram.

The housing or casing 1 is of cylindrical cross section and encloses a ring-like frame 35 2 having a plurality of spokes 3 extending inwardly from its perimeter and mounting the motor frame 4 at their inner ends. The left hand end of the motor shaft 5 mounts the fan 6 and the right hand end of the motor frame 40 mounts a pair of perforated plates 7 which grip the inner portion of an insulator member 8 which carries the heating elements 9 and 10 on a series of radial arms 8a.

A perforated reflector 11 is also attached 45 to the motor frame, this plate and plates 7 and 8 being secured to the frame by a screw 12. A therapeutic lamp 13 is mounted on a socket 14 attached to the casing 1 to the right of insulator 8.

50 The left hand end of the casing, although

reduced in diameter, is provided with a substantial opening which may be closed by a suitable plate 15. This plate mounts the switches 15, 16, 17 and 18 and the rheostat 19. The switch and the rheostat knob project through plate 15, as best shown in Figure 55 1. The wiring of the device is all contained within the casing 1, except the lead-in cable 20 and the cable 21 leading from the front of the device to the lamp socket 14.

The device, as a whole, is preferably mounted upon a yoke 22 by means of screws 23 extending through the ends of the yoke arms and the casing into frame 2.

By reference to the wiring diagram shown 60 in Figure 5, it will be seen that the switch 18 for the motor must be closed before either of the heating elements can function as the heating elements each have one terminal connected to the wire on the inner side of switch 18. This insures the operation of the fan whenever one of the heating elements is turned on and avoids undesirable heating of the device, due to careless inattention to the heat switches 15 and 16.

It is obvious, however, that the motor may be turned on without any of the heating elements being turned on. The same is true of the lamp 13 as its switch 17 is independent of the motor circuit.

The casing 1 is freely perforated at its 75 left hand portion, as indicated at 24, and these perforations, together with the open construction of the motor supporting elements and the supports for the heating elements and the reflector for the lamp 13, make for free passage of the air through the device which tends to cool the rheostat, cool the motor, and heat the air to the maximum degree for a given amount of current.

The mounting of the switches and rheostat on the removable plate at the left hand end of the casing enables the casing to be produced without any unsightly crevices and fastening devices or additional boxes for housing the elements for controlling the electrical apparatus and also provides for ready access to the switches and wiring in case the same need attention.

Obviously in a device of this kind, many 100

of the details may be varied without departing from the spirit of the invention and I contemplate such modifications in the structure as come within the scope of my claims.

I claim:

5. 1. In a device of the class described, a frame member, a motor mounted on said member, a fan on one side of said frame and driven by said motor, a pair of clamping elements secured to said motor on the other side of said frame, an insulator gripped between said elements, a reflector in front of said elements, and a lamp in front of said reflector, said frame, elements, insulator and reflector being constructed to allow an air stream to pass through the same and past said lamp.

2. In a device of the class described, a motor, fan and heating elements, a casing enclosing the same and having an enlarged main portion, a tapering discharge portion leading from one side thereof, and an offset portion of restricted diameter extending from the opposite side thereof, switches for said motor and heating elements mounted in said offset portion, said offset portion being provided with openings to admit air around said switches.

3. In a device of the class described, a motor, fan and heating elements, a casing enclosing the same and having an enlarged main portion, a tapering discharge portion leading from one side thereof, an offset portion of restricted diameter extending from the opposite side thereof, and having an open end, a removable plate closing said open end, and switches for said motor and heating elements mounted on the inner side of said plate with control lugs projecting therethrough.

4. In a device of the class described, a motor having a frame, a foraminous member extending across one end of said frame, a second foraminous member overlying said first mentioned member and projecting therewith to form an insulator holding clamp, a foraminous reflector overlying said second mentioned member, a screw extending through said reflector and members into said frame for securing said members and reflector in place on said frame, and a lamp in front of said reflector.

5. In a device of the class described, a cylindrical housing, a fan and a motor near one end thereof, an insulator carried by said motor, radially spaced circular heating elements in the path of the air stream from said fan on said insulator, a lamp in front of said heating elements a stationary reflector for said lamp within the periphery of the innermost heating element and extending between said lamp on one side and said insulator and said fan on the other side, said reflector being adapted to permit the passage therethrough of air from said fan.

6. In a device of the class described, a casing, a frame member, a motor carried there-

by, a fan driven by said motor, a stationary reflector mounted on said motor, an insulator carried on said motor and radially spaced circular heating elements on said insulator outside of the periphery of said reflector, said insulator being between said fan and said reflector, a lamp mounted on said casing in front of said reflector, said frame, insulator and reflector being foraminous to permit the passage of air therethrough from said fan and over said lamp.

In testimony whereof I hereunto affix my signature this 14th day of December, 1928.

WILLIAM G. SHELTON.
